EX
OR D 28,908

DESIGN.

H. L. JENKINS.

ILLUMINATED PANEL.

No. 28,908.

Patented June 21, 1898.

Witnesses: Inventor:
O. E. Van Doren, Harry L. Jenkins.
Richard Paul, By *Paul Hawley*
his attorney.

UNITED STATES PATENT OFFICE.

HARRY L. JENKINS, OF MINNEAPOLIS, MINNESOTA.

DESIGN FOR AN ILLUMINATED PANEL.

SPECIFICATION forming part of Design No. 28,908, dated June 21, 1898.

Application filed November 19, 1897. Serial No. 659,202. Term of patent 7 years.

To all whom it may concern:

Be it known that I, HARRY L. JENKINS, of the city of Minneapolis, county of Hennepin, State of Minnesota, have invented a certain 5 new and original Design for Illuminated Panels, of which the following is a specification, reference being had to the accompanying drawing, forming a part thereof.

The figure in the drawing represents a front 10 elevation of an illuminating-panel embodying my design.

The leading feature of the design, which is substantially rectangular, consists in the series of contrasting stripes, together with a contrasting rectangular section in the upper corner of the main rectangle, and a series of vertical lines, which with the stripes divide the

entire rectangle into a number of rectangular figures or spaces. In the drawing some of the stripes are shown as containing comparatively heavy longitudinally-extending lines and other stripes as containing lighter or finer longitudinally-extending lines. 20

What I claim is—

The design for an illuminating-panel, substantially as herein shown and described. 25

In testimony whereof I have hereunto set my hand this 15th day of November, A. D. 1897.

HARRY L. JENKINS.

In presence of—

RICHARD PAUL,
M. E. GOOLEY.
